DESIGN FOR A RANGE

Herman H. Heidbreder, Quincy, Ill., assignor to
Excelsior Stove and Manufacturing Co., Quincy,
Ill.

Application March 18, 1935, Serial No. 55,939

Term of patent 7 years

To all whom it may concern:

Be it known that I, Herman H. Heidbreder, a citizen of the United States and a resident of the city of Quincy, county of Adams, and State of Illinois, have invented a new, original, and ornamental Design for a Range, of which the following is the specification, and reference being had to

the accompanying drawing, forming a part thereof.

The figure is a perspective of my design for a range.

I claim:

The ornamental design for a range as shown.
HERMAN H. HEIDBREDER.
